[57] CLAIM

The ornamental design for an electronic address book, as shown.

DESCRIPTION

FIG. 1 is a right, front perspective view of an electronic address book with the cover closed showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a right, front perspective view thereof, with the cover shown in the open position.

FIG. 9 is a top plan view thereof;

FIG. 10 is a front elevational view thereof;

FIG. 11 is a left side elevational view thereof;

FIG. 12 is a right side elevational view thereof;

FIG. 13 is a rear elevational view thereof.

FIG. 14 is a bottom plan view thereof.
